Specification of Letters Patent. Patented Mar. 18, 1919.

Application filed January 10, 1918. Serial No. 211,724.

To all whom it may concern:

Be it known that I, CONRAD G. YOUNG, citizen of the United States, residing at Twin, in the county of Clallam and State of Washington, have invented a certain new and useful Improvement in Hosiery, of which the following is a specification.

My invention relates to improvements in hosiery as socks, stockings and the like and the object of my invention is to provide a comfortable, snug fitting sock or stocking that may be turned on the foot of the wearer to present new wearing surfaces for the heel and sole of the foot thereby increasing the life of such sock or stocking.

The novel shape and form herein disclosed is particularly well adapted for heavy socks that are worn by persons that do a great deal of walking but it will be understood that any class of hosiery may be advantageously constructed in accordance with my invention.

It is a well known fact that the heel of a sock or stocking is subjected to greater wear than the other parts thereof, and is usually the first part to wear out. It is the object of my invention to provide a sock of symmetrical shape so that it may be worn with different portions thereof under the sole and heel of the wearer to thereby distribute the wear.

This is accomplished by knitting or otherwise forming the sock in the shape of a tubular bag open at one end and having a rounded toe portion at the other end and provided at a distance from the toe with a section of enlarged diameter that serves as a heel and with a section of slightly reduced diameter just above the enlarged heel portion that makes the sock or stocking fit closely about the ankle.

The enlargement of the sock at the location of the heel gives the necessary room for the heel and ankle and affords a better and more comfortable fit than would be afforded by a straight sock that did not have the enlarged portion at the location of the heel.

In the drawings the figure is a view in elevation illustrating a sock constructed in accordance with my invention as it might appear when spread out on a flat surface, the top of the sock being shown as folded.

Referring to the drawings throughout which like reference numerals designate like parts the numeral 5 designates the foot portion and 6 designates the leg or upper portion of a sock.

The foot portion 5 and leg portion 6 are of the usual circular or tubular shape and are connected with each other by a heel portion 7 of larger diameter than either the leg or foot portions.

The leg, heel and foot portions are disposed in alinement with each other so that they present substantially the appearance 65 of a symmetrical leg having an enlargement or fullness at the heel portion.

If the sock is knit as shown in the drawings, the enlarged heel portion 7 may be formed by knitting in gussets, as indicated 70 at the position 8 at a plurality of points around the heel portion thereby giving the heel portion the desired fullness.

To secure a better fit around the ankle and prevent wrinkling and folding of the 75 enlarged heel portion 7 on the sides and top of the foot I have caused that part of the leg portion 6 just above the heel to be narrowed or reduced in diameter as indicated at 9.

In use the sock is placed on the foot in any position, the enlarged portion 7 forming a heel regardless of the position in which the sock is turned and the elasticity of the 85 yarn allowing the leg portion to be drawn into a position substantially at right angles to the foot portion so that the sock will fit snugly about the ankle without wrinkling or folding.

Since the sock is symmetrical it may be 90 put on in a different position each day to bring a different part of the sock under the foot of the wearer and thereby insure equal wear at all points around the circumference of the foot portion of the sock or it may be 95 worn in one position until the heel or foot portion shows signs of wearing out and may then be turned to bring fresh material, that has hitherto been worn on the sides or top of the foot, under the foot and heel.

It is obvious that the enlarged heel portion may be formed in the sock in various ways other than knitting in gusset portions 8 as shown in the drawings.

What I claim is:

A hose of the class described comprising a foot portion having a leg portion formed in prolongation thereof, and a plurality of 5 gussets in the hose at the point of connection of the foot portion with the leg portion whereby a heel pocket is provided in any

position in which the hose is worn and the hose snugly and smoothly fits the foot without wrinkling or folding at the instep.

In witness whereof, I hereunto subscribe my name this 2nd. day of January A. D., 1918.

CONRAD G. YOUNG.
